(57) **CLAIM**

The ornamental design for a medical device, as shown and described.

DESCRIPTION

FIG. 1 is a left side elevational view of a medical device according to the present invention;

FIG. 2 is a right side elevational view of the medical device of FIG. 1;

FIG. 3 is a front elevational view of the medical device of FIG. 1;

FIG. 4 is a rear elevational view of the medical device of FIG. 1;

FIG. 5 is a top plan view of the medical device of FIG. 1;

FIG. 6 is a bottom plan view of the medical device of FIG. 1;

and,

FIG. 7 is a three quarter view of the medical device of FIG. 1. The dashed lines illustrate environment that does not form a part of the present invention, and no claim is made to the material illustrated with dashed lines.

1 Claim, 6 Drawing Sheets

FIG. 1

FIG. 2

FIG. 4

FIG. 3

FIG. 5

FIG. 6

FIG. 7
